UNITED STATES PATENT OFFICE.

JOHN F. DODGE, OF DETROIT, AND HORACE E. DODGE, OF GROSSE POINTE, MICHIGAN,
ASSIGNORS TO DODGE BROTHERS, OF DETROIT, MICHIGAN, A CORPORATION OF
MICHIGAN.

CYLINDER-HEAD.

1,197,109.

Specification of Letters Patent. Patented Sept. 5, 1916.

Application filed October 2, 1914. Serial No. 864,593.

To all whom it may concern:

Be it known that we, JOHN F. DODGE and HORACE E. DODGE, citizens of the United States, residing at Detroit, Michigan, and 5 Grosse Pointe, Michigan, respectively, have invented certain new and useful Improvements in Cylinder-Heads, of which the following is a clear, full, and exact description.

10 This invention relates to heads for the cylinders of engines, and some of the objects of the invention are to provide a cylinder head which possesses certain advantages from a manufacturing point of view; 15 also to provide for the even distribution of water throughout the entire area of the head; also to provide a cylinder head of considerable strength and rigidity having means for supporting the cylinder head 20 wall.

Another object of the invention is to provide a combined water header and cylinder head.

These being among the objects of the 25 present invention the same consists of certain features of construction and combinations of parts to be hereinafter described and then claimed with reference to the accompanying drawings illustrating a suitable embodiment of the invention, in which—

Figure 1 is a plan view partly in dotted lines; Fig. 2 is an underside view also partly in dotted lines; Fig. 3 is a section 35 on the line 3—3 Fig. 1; Fig. 4 is a section on the line 4—4 Fig. 1; Fig. 5 is an enlarged transverse section on the line 5—5 Fig. 1; Fig. 6 is an enlarged transverse section on the line 6—6 Fig. 1; and Fig. 7 is a 40 sectional detail on the line 7—7 Fig. 1.

Referring to the drawings, the improved cylinder head is preferably made as a hollow metal casting with bottom and top walls 10, 11 respectively, said walls being suitably spaced apart. The bottom wall 10 is provided with one or more depressions, as 45 12, 13, 14 and 15 which are in line with each other and so arranged as to form the upper ends of the cylinders of the engine. The 50 upper and lower walls 11, 10 are connected by a series of posts for different purposes. If there are four cylinder depressions 12, 13, 14 and 15, there will be four hollow 55 spark plug posts 16, 17, 18 and 19, there being one post for each depression, each

post connecting the wall of the depression with the top wall of the cylinder head. There will also be four hollow posts 21, 22, 23 and 24 to correspond with the four depressions mentioned, and these hollow posts 60 form priming cock holes, so that there is one of these paired with each spark plug hole, but these hollow posts are preferably smaller than the spark plug posts. These posts constitute means for reinforcing and 65 bracing the cylinder head wall at the depressions. All of said posts are preferably in alinement as shown in Figs. 1 and 2, and the upper wall 11 is provided with a recess such as 25 at the upper end of each of the 70 spark plug posts.

To one side of the cylinder head as shown in dotted lines in Fig. 1 and in the cross sections there is located a series of spaced ribs or webs 26, 27 and 28, and these webs 75 extend partly over the depressions or cylinder head walls so as to reinforce and strengthen them.

At the top of the cylinder head is a longitudinal channel member 29 located to one side of the cylinder head adjacent to the said ribs 26, 27 and 28 and this channel member or water outlet header section is provided with an outlet 30. Around the edge of the cylinder head there are located 80 a series of holes 31 for the studs and the walls surrounding these holes at the inner or chambered side of the cylinder head are in the nature of posts as indicated. Other stud holes are formed by hollow posts such 85 as 32, which are formed at their upper ends into recesses 33 in the top wall of the cylinder head. The bottoms of the recesses 33 constitute seats for the stud nuts, depressed below the upper surface of the top wall 11, 90 while preferably the material of the top wall at the upper ends of the stud holes at the edge of the cylinder head is raised above the surface of the top wall so as to constitute raised seats for the stud nuts. 95

The described construction of cylinder head constitutes a very strong and substantial device. The course of the water through the cylinder head is as follows: It is drawn from the radiator to the pump and forced into the cylinder jacket, and then out through openings 34 formed in the outer edge of the lower wall 10 of the cylinder head, the water then passing throughout the cavities of the cylinder head and up- 100 105 110

wardly through apertures 35, 36 in the top wall 11 and into the channel member 29, from whence the water passes out through the outlet 30 and goes back to the radiator.

- 5 Attention is directed to the fact that in the illustrated construction the top wall 11 of the cylinder head constitutes the bottom wall of the outlet header or channel member 29, thus making said top wall serve 10 two functions. The apertures 35, 36 of said top wall are also of such size and so spaced apart, toward the ends of the said wall, as to give an even pull, along the water line, from the rear and front pairs of cylinders. 15 In other words, these apertures are so located with respect to the cylinders and so proportioned in size, that they tend to distribute the pump-impelled circulation uniformly over the cylinders.
- 20 It will be noted that the cylinder head construction herein illustrated and described provides a water chamber in which a free circulation of the water over the parts to be cooled can take place, and, moreover, 25 that the construction of the posts through which the spark plug openings and priming openings are led into the cylinder is such that a very effective reinforcement of the cylinder head is obtained without unsightly 30 and objectionable protuberances either upon the outside of the cylinder head or upon the inside of the cylinder. The maintenance of a smooth interior surface is particularly desirable in that it prevents the excessive accumulation of carbon and other foreign substances in the cylinder and this constitutes 35 one of the important features of the invention.

It is obvious that this invention is susceptible of modification, as parts may be omitted, parts added and parts modified without departing from the invention as expressed in the claims.

What we claim as new is:—

- 45 1. A cylinder head for multi-cylinder engines, having spaced walls, one of which forms a part of the end walls of cylinders arranged in line, and elongated ribs integrally connecting said walls, said ribs being 50 arranged lengthwise in line along the line of cylinders and spaced in said line to provide transverse circulation directing openings.

55 2. A cylinder head for multi-cylinder engines, having spaced walls, one of which forms a part of the end walls of cylinders arranged in line, and elongated ribs integrally connecting said walls, said ribs being 60 arranged lengthwise in line along the line of cylinders and being spaced opposite the ends of said cylinders.

65 3. A cylinder head for multi-cylinder engines, having spaced walls forming a water chamber, one of said walls forming a part 65 of the end walls of cylinders arranged in

line, posts integrally connecting and backing said spaced walls, some of said posts being provided with spark-plug receiving openings and others of said posts being provided with priming openings, and relatively thin elongated ribs integrally connecting 70 said spaced walls and arranged in line along the line of cylinders, said line of ribs being provided with transverse circulation directing openings.

4. A cylinder head for multi-cylinder engines having spaced walls forming a water chamber and one of which forms a part of the end walls of cylinders arranged in line, posts integrally connecting said spaced walls 80 near one side of said line of cylinders, said posts being provided with openings ending flush with the inner walls of the cylinders, and relatively thin elongated ribs integrally connecting said spaced walls near the other side of said line of cylinders and arranged in line along said line of cylinders, said line of ribs being provided with transverse circulation 85 directing openings.

5. A cylinder head for multi-cylinder engines, having spaced walls forming a water chamber, one of said walls forming a part of the end walls of cylinders arranged in line, a water header located upon the other wall and of which said wall forms the bottom, posts integrally connecting and backing 90 said spaced walls and located wholly within said chamber, and ribs integrally connecting said walls, said posts being located upon one side of said header and said ribs upon the other side.

6. A cylinder head for multi-cylinder engines, comprising a hollow body with top and bottom walls and constituting a cylinder end water jacket, and elongated circulation directing ribs connecting said walls and extending along the line of the desired flow of the water through said jacket, said line of ribs being provided with transverse circulation directing openings over the cylinder ends.

7. A cylinder head for multi-cylinder engines, having spaced walls forming a water chamber, one of said walls constituting also the end walls of cylinders arranged in line, 115 said head having along its sides inlet openings for the water, and circulation directing ribs arranged in line along the line of cylinders, said line of ribs being provided with transverse circulation directing openings.

8. A cylinder head for multi-cylinder engines, comprising a hollow body with top and bottom walls which form a water chamber, said walls each having a series of depressions into said chamber, the depressions 125 of the two walls being opposed but spaced, hollow posts connecting said opposed depressions in the two walls, and ribs connecting said walls and extending over the said depressions of the bottom wall but spaced 130

to provide transverse openings over said depressions.

9. A cylinder head for multi-cylinder engines, comprising a hollow body with top and bottom walls which form a water chamber, said walls each having a series of depressions into said chamber, the depressions of the two walls being opposed but spaced, hollow posts connecting said opposed depressions in the two walls, and ribs connecting said walls and extending over the said depressions of the bottom wall in substantial alinement, near one side of said body, said line of ribs being provided with transverse openings over said depressions.

10. A cylinder head for multi-cylinder engines, comprising a hollow body with top and bottom walls which form a water chamber, said walls each having a series of depressions into said chamber, the depressions of the two walls being opposed but spaced, hollow posts connecting said opposed depressions in the two walls, and ribs connecting said walls and extending over the said depressions of the bottom wall in substantial alinement, but spaced endwise to form a non-continuous partition near one side of said body, said bottom wall being provided with water inlet apertures.

11. A cylinder head for multi-cylinder engines, comprising a hollow body with top and bottom walls which form a water chamber, said walls each having a series of depressions into said chamber, the depressions of the two walls being opposed but spaced, hollow posts connecting said opposed depressions in the two walls, and ribs connecting said walls and extending over the said depressions of the bottom wall in substantial alinement, but spaced endwise to form a non-continuous partition near one side of said body, said bottom wall being provided with water inlet apertures, and a water-outlet header-member extending longitudinally along that side of the top wall adjacent said ribs and communicating with the water space of said body.

12. A cylinder head for multi-cylinder engines, comprising a hollow body having a top wall and a bottom wall, and constituting a water jacket, said bottom wall forming the end wall of cylinders arranged in line, and an outlet header extending along said top wall, said top wall constituting the bottom of said outlet header and being provided with circulation directing and controlling apertures located at different points spaced along said line of cylinders and affording communication between said water jacket and said header.

13. A cylinder head for multi-cylinder engines, having spaced walls forming a water chamber, one of said walls constituting also the end walls of the cylinders, a water

header upon the other wall and of which said wall forms the bottom, said wall being provided with apertures affording communication between said water chamber and said header, and said apertures being so proportioned to the rate of flow and so spaced and located over the cylinders with respect to the general direction of the circulation of the water through said header and through said water chamber that they direct the circulation and distribute it substantially equally over the cylinders.

14. A cylinder head for multi-cylinder engines, having spaced walls forming a water chamber, one of said walls constituting also the end walls of the cylinders, an outlet header upon the other wall and of which said wall forms the bottom, said header having an outlet opening and being constructed to direct the water to said opening, and said bottom wall being provided with circulation directing and controlling apertures so spaced and located with respect to the cylinders and so proportioned that they tend to distribute the circulation uniformly over the cylinders.

15. A cylinder head for multi-cylinder engines, comprising a hollow body having a top wall and a bottom wall and constituting a water jacket, said bottom wall forming the end wall of cylinders arranged in line, and an outlet header extending along said top wall and along the line of cylinders and constructed to conduct the circulating water to one end of said line, said top wall of said body constituting the bottom of said outlet header and being provided with apertures so spaced and located with respect to the cylinders and with respect to the direction of movement of the water through the header that they tend to distribute the circulation equally over the cylinders.

16. A cylinder head for multi-cylinder engines, comprising a hollow body having a top wall and a bottom wall and constituting a water jacket, said bottom wall forming the end walls of a series of cylinders arranged in line and an outlet header extending along said top wall and along the line of cylinders, which wall constitutes the bottom of said outlet header, and is provided with apertures, within said header, said apertures being spaced apart and located near the ends of said top wall.

17. A cylinder head for multi-cylinder engines, having spaced walls forming a water chamber, one of said walls constituting also the end walls of cylinders arranged in line, said head having along its sides inlet openings for the water, means along the sides for directing the water over the cylinder ends, said means being spaced to provide an uninterrupted passage for the water along the line of cylinders, and an outlet header located over said uninterrupted pas-

sage and separated therefrom by the outer wall of said chamber, communicating openings between said header and said passage being formed in said wall at points spaced 5 along the line of cylinders.

18. A cylinder head for multi-cylinder engines comprising a hollow body having spaced top and bottom walls forming a water chamber, one of said walls constituting also the end walls of the cylinders and said head having inlet openings along its sides for the cooling water, ribs connecting said top and bottom walls and so spaced and arranged with respect to said 10 inlet openings as to direct the water over the cylinder ends, posts also connecting said top and bottom walls and so located with respect to said inlet openings as to direct the water over the cylinder ends, said posts 15 and ribs being so arranged with respect to each other as to provide an uninterrupted passage over the cylinder ends, and a water header upon said top wall over said uninterrupted passage, said wall being provided 20 in said header with openings by which said water chamber communicates with said header.

19. A cylinder head for multi-cylinder engines, comprising a hollow body having spaced top and bottom walls forming a water chamber, said bottom wall forming the ends of cylinders arranged in line and having inlet openings along the sides of said head for the cooling water, ribs arranged in line along one side of the line of cylinders and spaced to direct the circulating water over the cylinder ends, posts connecting said top and bottom walls and so arranged toward the other side of the line 35 of cylinders as to direct the circulating water coming in at that side of the line over the cylinder ends, said line of ribs and said posts being spaced to provide an uninterrupted passage over the cylinder ends along 40 the line of cylinders, and a water header located above said passage and separated therefrom by the top wall, said wall being provided with openings of such size and so spaced as to direct the circulation substantially 45 equally over the cylinder ends.

20. A cylinder head for multi-cylinder engines, comprising a hollow body having spaced top and bottom walls forming a water chamber, said bottom wall forming the ends of cylinders arranged in line and having inlet openings along the sides of said head for the cooling water, ribs arranged in line along one side of the line of cylinders and spaced to direct the circulating 55 water over the cylinder ends, posts connecting said top and bottom walls and so arranged toward the other side of the line of cylinders as to direct the circulating water coming in at that side of the line 60 over the cylinder ends, said line of ribs and

said posts being spaced to provide an uninterrupted passage over the cylinder ends along the line of cylinders, and a water header located above said passage and separated therefrom by the top wall, said 70 header being constructed to discharge at one end of the line of cylinders, and said wall being provided with openings into said header located near the ends of said line.

21. A cylinder head for multi-cylinder engines, having spaced walls forming a water chamber, one of said walls constituting also the end walls of cylinders arranged in line, said head having along its sides inlet openings for the water, and circulation 80 directing ribs connecting said walls and arranged in line along the line of cylinders, said ribs backing and reinforcing the cylinder ends and being spaced opposite the middle portion of said cylinder ends to insure 85 a circulation of the water over the cylinder ends crosswise of the line of cylinders.

22. A cylinder head for multi-cylinder engines, having spaced walls forming a water chamber, one of said walls constituting also the end walls of cylinders arranged in line, a water header located upon the other wall and of which said wall forms the bottom, and circulation directing ribs extending in line along the line of cylinders, 90 said line of ribs being provided with transverse circulation directing openings and said bottom wall of said water header being provided with circulation directing and controlling apertures spaced along the line of 95 cylinders.

23. A cylinder head for multi-cylinder engines, having spaced walls forming a water chamber, one of said walls constituting also the end walls of cylinders arranged in line, a water header located upon the other wall and of which said wall forms the bottom, and circulation directing ribs arranged in line along the line of cylinders, said line of ribs being provided with transverse circulation directing openings and said cylinder head having along its sides inlet openings for the water, the bottom wall of said water header being provided with circulation directing and controlling 105 apertures spaced along said line of cylinders.

24. A cylinder head for multi-cylinder engines, having spaced walls forming a water chamber, one of said walls constituting also the end walls of cylinders arranged in line, an outlet header upon the other wall and of which said wall forms the bottom, and circulation directing ribs arranged in line along the line of cylinders and at one side of said outlet header, said cylinder head having inlet openings upon the side of said line of ribs remote from said outlet header, and said line of ribs being provided with transverse circulation directing openings, 120 125 130

the bottom wall of said header having apertures providing communication between said header and said chamber.

25. A cylinder head for multi-cylinder engines, having spaced walls forming a water chamber, one of said walls constituting also the end walls of cylinders arranged in line, circulation directing ribs arranged in line along the line of cylinders, said line of ribs having transverse circulation directing openings opposite the cylinder ends, and an outlet header upon the other wall of said chamber and of which said wall forms the bottom, said header being constructed to 15 discharge the water at one end of said line of cylinders and having circulation directing and controlling apertures in its bottom located near the respective ends of said line of cylinders.
26. A cylinder head for multi-cylinder engines, having spaced walls forming a water chamber, one of said walls constitut-

ing also the end walls of cylinders arranged in line, said cylinder head having along its sides inlet openings for the water, circulation directing ribs arranged in line along the line of cylinders and spaced opposite the cylinder ends to provide transverse circulation directing openings, an outlet header on the outer wall of said chamber 30 and of which said wall forms the bottom, said outlet header extending along the line of cylinders and having in its bottom apertures providing communication with said chamber and located at points spaced along 35 the line of cylinders.
